UNITED STATES PATENT OFFICE.

LEROY M. LEWIS, OF PHILADELPHIA, PENNSYLVANIA.

PROCESS OF MAKING FUSIBLE LINKS.

1,382,368.

Specification of Letters Patent. Patented June 21, 1921.

Application filed May 6, 1920. Serial No. 379,253.

To all whom it may concern:

Be it known that I, LEROY M. LEWIS, a citizen of the United States, and a resident of the city of Philadelphia, county of

5 Philadelphia, and State of Pennsylvania, have invented certain new and useful Improvements in Processes of Making Fusible Links, of which the following is a specification, reference being made to the accompanying drawings, illustrating one mode of performing the process of my invention.

The invention relates to a process of making fusible links of the type disclosed in my copending applications for United States 15 Letters Patent, Serial Numbers 292,409 and 368,888, filed April 24, 1919, and March 26, 1920, respectively.

Among the objects of my invention is to form a link structure with elements which 20 will properly be retained in the sprinkler head against premature operation and which will operate efficiently upon the fusing of the fusible material between the elements thereof.

25 I have discovered, in making or forming plates for fusible links, that by first laterally offsetting a portion of each plate at the place finally shaped into laterally bent portions, between which a strain member 30 may be located when the plates are assembled, and then pressing, with a properly formed die, against the offset portion to return the same to the finished or desired shape to form the laterally projecting socket

35 portions of the plates, a greatly improved plate is produced. In previous methods of making these plates, the central portion of the plate was subjected to a die action which, in effect, was a "drawing" action, the

40 portion acted upon by the dies being "drawn" or stretched from the remainder of the plate to form a laterally extending socket portion, in which was located a strain element. This made the plate thin or weak

45 at certain points, particularly at the lines where the edges of the strain member were seated, the weakened part having to receive the full force of the strain applied to the link. I have discovered that by reversing

50 the dies and by first offsetting a central portion of a plate blank and then subjecting the offset portion to compressing die action to return said offset portion to the desired form, the drawn and weakened portions are wholly avoided, and a strong, tough and accurately made plate is produced.

It is therefore an object of my invention to provide a process consisting of the steps essential to produce the desired result above indicated.

Another object of my invention is to carry out the steps of the process to effect an economy of material, greatly reducing the waste incidental to the processes heretofore in use.

Such other advantages and objects as are present in my new and improved process will more fully appear in the following specification.

Referring to the drawings in which I illustrate the steps of the process that may be utilized in this invention,

Figures 1 and 2 are views respectively in elevation and plan of an end of a strip of metal from which the link plates may be made;

Figs. 3 and 4 are views respectively in elevation and plan of the same showing the steps of offsetting a portion;

Figs. 5 and 6 are similar views of the offset blank cut from the strip shown in Figs. 3 and 4;

Figs. 7 and 8 respectively show sectional and plan views of a blank cut and pierced to the particular plate shape or configuration desired;

Figs. 9 and 10 are similar views of the finished plate showing the shape of the socket portion formed in the plate;

Fig. 11 is a view in section of the compressing dies and an offset blank prior to the die pressing action;

Fig. 12 is a similar view at the end of the die operation showing the finished shape of the socket portion in the plate;

Fig. 13 is a section, on an enlarged scale of a plate formed by the method hitherto in use and showing the points of weakness therein; and

Fig. 14 is a similar view of a plate formed in accordance with this invention and showing the strengthened parts thereof.

Referring now more particularly to the drawing, in which the same reference characters are used to designate corresponding parts in the various views illustrated, in forming the plates a metal strip 1 of indefinite length may be fed from a suitable source into a two-station die press, (not shown), in the first station of which the strip 1 may be upset or offset to produce a substantially semicircular offset portion

2 as clearly shown in Figs. 3 and 4 of the drawing, which is then fed to the second station of the press where the end of the strip may be cut off to form the blank 3 5 as shown in Figs. 5 and 6, such blank being provided with the offset portion 2 substantially at the center thereof. The type of die press used for this may be of any suitable construction, and its illustration here 10 is deemed unnecessary. The blank 3 may then be placed into another die press where the blank is suitably trimmed and pierced to produce the blank 4 of the contour illustrated in Figs. 7 and 8 of the drawing or 15 other suitable contour, the central aperture 5 being pierced through the offset portion 2 of a purpose hereinafter more fully described.

The blank 4 may then be transferred to 20 the compression die press, which may be of the coin die press type, in which a male die 6 is placed in the lower die head 7 and a female die 8 is carried by the upper die head. The die 6 may be located in a socket 9 provided in the die head 7 and adapted to 25 freely move vertically therein. The dies and the socket are preferably of the same contour as the plate 4. The die 6 may be suitably supported upon a plunger 10 adapted to 30 freely move through the aperture 11 provided in the lower portion of the head 7. The plunger 10 may be connected to any suitable part of the die press whereby the die 6 may be returned to its raised position 35 after a die operation. Upwardly projecting portions or pilot pins 12 and 13 may be provided on the die 6 to register with the sockets 12' and 13' of the die 8 whereby the two dies and the plate 4 may be maintained in proper relation as the parts approach each 40 other, the projections also serving to prevent lateral crawl of the plate during the operation of the dies.

In operation, the blank 4 is placed upon 45 the die 6 with the projections 12 and 13 extending upwardly through the apertures 14 and 5 of the plate 4 and with the offset portion 2 extending upwardly and located over the die surface 15 of the lower die 6, the portion 16 of the head being guided in 50 the notch 17 of the plate 4, as the latter is caused to descend. It will be observed that the side walls of the socket 9 are slightly inclined from the vertical to converge downwardly whereby, as the plate 4 is forced 55 downwardly within the die 6, the edges of the plate 4 will be slightly compressed so that as the plate is lowered to the position shown in Fig. 12, the plate will be slightly 60 smaller in contour or area. When the plunger 10 moves upwardly with the die 6 from the position shown in Fig. 12 to that shown in Fig. 11, the plate 4 will not bind in the socket 9 and may be readily removed either 65 by hand or by any suitable means provided

on the press. The die 6 is placed in the lower position, relative to the die 8, with the projection 15 directed upwardly beneath the offset portion 2 of the plate 4, while the recess 15' of the die 8 is located 70 immediately above the offset 2. When the press is operated, the die 8 approaches the die 6 and compresses the offset portion 2, causing it to flow or be pressed into the form shown, on an enlarged scale, in Fig. 14 so 75 that the angles or recesses in the die surfaces will be completely filled with the metal of the offset portion 2. The resultant socket portions 19 thus formed in the plates are of uniform thickness, tough, strong and 80 correctly shaped to efficiently retain, with greater tension capacity, the strain element or the key located in the socket formed between such portions in the assembled link. It will be observed that the material or web 85 between the socket portion 19 and the adjacent portion 20 of the plate is not "drawn-out" and weakened as in the old form of plates.

In the old process the dies are located in 90 reverse relation and as the projection of the male die is forced against the plate 21 (see Fig. 13), the portion 22 of the plate is formed by a drawing action causing a narrowing or constricture 23 between the portion 22 and the portion 21' of the plate. The web portion 23 thus formed is weak 95 and provides a poor shoulder against which the edge of the strain member must bear when the link is assembled and placed under pressure. In addition to the above, such plate also has another constricted and weakened portion 24, similarly formed.

In my device the offset portion 2 is formed without any drawing action or stretching 105 of the strip 1, the strip 1 being fed forward during the lateral up-setting or offsetting of the portion 2 sufficiently to compensate for the same. Then, by subjecting this offset portion to compressing die actions the 110 same will be caused to flow back into the final form of socket portion desired, as is clearly shown in Fig. 14, so that the socket portions 19 will have sharp corners 25 and 26. The latter, it will be observed, will receive the edge of the strain member or key 115 without any tendency of the latter to slide over the corner 27 and consequently the line of strain through the strain member may be brought nearer the center plane of the link 120 assembly. In the old form of key, the corner 27' is rounded due to the drawing action of the dies, and the strain member or key will not rest squarely upon the portion 23 but is constantly urged to move over the 125 rounded portion 27' tending to wedge the plates apart, a condition that is obviously undesirable and which often causes premature operation of the link structure.

I have found, by my new process of mak- 130

ing link plates, an economy in material is secured, that the plates are tougher, more accurately formed and capable of more efficiently retaining the strain member. Inasmuch as the tension capacity is greater, the angle of the socket portions need not be as great as in the prior forms and a thinner link may thus be produced with the line of strain nearer to the central plane of the assembly.

While I have herein shown one mode of carrying out my invention, it is to be understood, however, that the latter is not limited to the particular steps or operations herein described and illustrated on the accompanying drawings, but that other modes are comprehended thereby without departing from the spirit of the invention and the scope of the appended claims.

Having thus described my invention, what I claim and desire to protect by Letters Patent of the United States is:

1. The process of making a plate for a fusible link which comprises the steps of forming a transversely extending offset in a metal blank, placing the blank in a die press and compressing said offset portion to form a flat portion angularly disposed relative to the body portion of the finished plate and connected thereto by a web of thickness substantially equal to that of said body portion.

2. The process of making a plate for a fusible link which comprises the steps of forming a curved transversely extending offset in a blank, placing the blank in a die press comprising male and female dies and compressing said blank into conformity with the shape of said dies, whereby said offset portion is transformed to a flat portion angularly disposed with respect to the body of the plate and connected thereto by a web of thickness substantially equal to the body portion.

3. The process of forming a plate for a fusible link which comprises the steps of forming in a metal blank a transversely extending offset with the metal in the offset portion of substantially the thickness of the metal of the blank, placing said blank in a die press comprising male and female dies and compressing said blank by causing said dies to approach each other, whereby said offset is transformed to two normally positioned integral portions each connected with the body of the blank and angularly disposed with respect thereto.

4. The process of making a plate for a fusible link which comprises the steps of laterally dishing a flat blank to form a curved offset thereon of substantially the same thickness as the body of the blank, placing the blank with said offset projecting upwardly upon the upper face of the male member of a die and compressing the blank

against said member by moving the female member of the die downwardly against the blank, whereby the blank is caused to assume the shape of the dies and the offset portion is transformed to a flat portion angularly disposed with respect to the body portion of the finished plate and connected thereto by a web of thickness substantially equal to said body portion.

5. The process of making a plate for a fusible link which comprises the steps of laterally offsetting a strip of flat stock to form a substantially semi-circular offset of substantially the same thickness as the body of the strip, severing a blank including the offset from the strip, placing the blank upon the male member of a die having an upwardly projecting portion with said offset over said upwardly projecting portion, and compressing the blank against said member by moving the female member of the die downwardly against the blank, whereby the blank is caused to assume the shape of the dies and the offset portion is transformed to a flat portion angularly disposed with respect to the body portion of the finished plate and connected thereto by a web of thickness substantially equal to said body portion.

6. The process of making a plate for a fusible link which comprises the steps of laterally offsetting a strip of flat stock to form a substantially semi-circular offset of substantially the same thickness as the body of the strip, severing a blank including said offset from the strip, placing the blank with said offset extending upwardly upon the male member of a die conformable to the contour of one side of the finished plate and having an upwardly projecting portion adapted to enter said offset and compressing the blank against said male member by bringing the female member of the die which is conformable to the other side of the finished plate against the upper surface of the blank, whereby the metal in the offset of the blank is caused to flow to assume the shape of the adjacent portion of the dies and is transformed to two normally positioned portions each connected with the body of the blank and angularly disposed with respect thereto.

7. The process of making a plate for a fusible link which comprises the steps of laterally offsetting a strip of flat stock to form a substantially semi-circular offset of metal of substantially the same thickness as the body of the strip, severing a blank including the offset from the strip, cutting and piercing the blank to desired shape, placing the blank, with the open side of the offset downward upon the male member of a die having an upwardly projecting portion adapted to enter the offset and then compressing the blank against said male member

by first bringing the female member of the die against the upper surface of the offset prior to contact of the other portions of the member with the rest of the upper surface of the blank, whereby the metal in the offset portion of the blank is caused to flow to assume the shape of the dies and is trans-

formed in two integral normally disposed webs forming a V-shaped offset in the finished plate integral with the body portion 10 thereof and in angular relation therewith.

In witness whereof, I have hereunto set my hand this 30th day of April, 1920.

LEROY M. LEWIS.
